UNITED STATES PATENT OFFICE.

WILLIAM J. HELLER, OF EASTON, PENNSYLVANIA.

DESIGN FOR A FLAG-HOLDER.

46,363.

Specification for Design.

Patented Sept. 8, 1914.

Application filed February 28, 1914. Serial No. 821,813. Term of patent 14 years.

To all whom it may concern:

Be it known that I, WILLIAM J. HELLER, a citizen of the United States, residing at Easton, in the county of Northampton and State of Pennsylvania, have invented a new, original, and ornamental Design for Flag-Holders, of which the following is a specification, reference being had to the accompanying drawing, forming a part thereof.

In the drawings: Figure 1 is an elevation of the device illustrating my new design, Fig. 2 a plan view of the same, and Fig. 3 a side elevation.

I claim:

The ornamental design for a flag holder, as shown.

WILLIAM J. HELLER.
